CLIP-ON ARTICLE HOLDER FOR SUN VISORS

Dee J. Wheeler, Denver, Colo.

Application April 14, 1955, Serial No. 35,508

Term of patent 14 years

(Cl. D14—6)

Fig. 1 is a front perspective view of a clip-on article holder for sun visors showing my design; and

Fig. 2 is a left end elevation of the clip-on article holder shown in Fig. 1.

I claim:

The ornamental design for a clip-on article holder for sun visors as shown.
